AIRPLANE KITE

Walter A. Wood, Los Angeles, Calif., assignor to
John D. Chesnut, San Marino, Calif.

Application December 21, 1935, Serial No. 55,590

4 Claims. (Cl. 244—154)

My invention relates to improvements in airplane kites, which are kites flown on a string or wire and having the general appearance of an airplane. More particularly the invention relates to improvements in kite construction which provide a kite which flies easily and by a simple adjustment, can be made to fly with great stability or can be made to stunt.

A principal object of the invention is to provide a kite having wing surfaces which are curved about their lateral axes to provide concave lower wing surfaces resulting in easy flying and stability.

Another object is to provide a wing construction wherein the outer tip of each wing covering is flexible and can readily conform to the concave curvature of the remainder of the wing, while the frame work of the wing is relatively rigid.

Another object is to provide wings and elevators which are quickly and easily adjustable to convert the kite from a stable flying kite to a stunting kite, or vice-versa.

Another object is to provide a kite having a nose which is easily replaceable in case of damage.

Another object is to provide a framework which is easily covered with paper or fabric and which may be quickly and easily assembled.

Another object is to provide a wind-operated noise making device which simulates the sound of an airplane engine.

Another object is to provide a construction which is substantially two-dimensional, but which has the appearance of a full three-dimensional device when viewed from any angle.

Another object is to provide a kite which is light, but strong, and of simple construction.

Other objects and advantages will appear from the following descriptions and drawings wherein:

Fig. 1 shows a perspective view of the kite framework with the covering removed.

Fig. 2 shows a side elevation of the kite framework.

Fig. 3 shows a plan view of framework of one form of elevator.

Fig. 4 shows a plan view of the framework of an alternative form of elevator.

Fig. 5 illustrates the manner in which the wing covering bellies in the wind when free of the wing frame at both ends.

Fig. 6 illustrates the manner in which the wing covering bellies in the wind when free of the wing frame at the outer ends only.

The main body or fuselage of the kite is formed by a pair of bowed members (such as bamboo sticks); 1 and 2 brought together and fastened at their rear ends, 3. The members 1 and 2 are spaced apart at their forward ends and are fastened to an upright 4. A brace, 5, is fastened between the members 1 and 2 to the rear of post 4. Post 4 extends above and below the members 1 and 2, respectively, and at its lower end is fastened to a cross piece or axle, 6, which is provided at its outer ends with wheels, 7. A pair of brace members, 8 and 8a are fastened at their ends to the axle, 6, and post 4. If desired, a bowed piece, 9, may be detachably connected at its ends to post 4, as by means of brackets, 49, and bolts, 50.

A pair of laterally extending wings are attached to the fuselage. Each wing comprises a pair of parallel spaced members 11—11a and 12—12a. The members 11—11a and 12—12a are each connected by a pair of spaced cross braces 13—13a and 10—10a, respectively. A pair of diagonally crossed braces, 14 and 14a are connected at their ends to the respective braces, 13—13a, near the lateral members 11—11a. The other wing is similarly braced.

In order to give the wing framework a bowed contour about its lateral axis, suitable cords or wires, 15, are connected across the under surface of each wing. To engage the cords, 15, each of the cross braces, 13 and 13a, extends slightly beyond the respective lateral members 11—11a and 12—12a. The cords are drawn tight to impart a bow to the framework. The outer ends of each pair of lateral members 11—11a and 12—12a, are connected by a cross brace, 16 and 16a. A slack cord, 11—11a (Fig. 3) connects the outer tips of the lateral members 11—11a and 12—12a, the slackness being sufficient to permit a curvature equal to the bow of the wings. The wing covering is fastened to the cords, 17 and 17a, and not to the cross braces, 16 and 16a.

The wings are fastened to the fuselage in such a manner that they can be readily tilted to either raise or lower the leading edge with respect to the trailing edge in order to vary the angle of incidence. This may be accomplished by raising or lowering either edge, but I prefer to raise and lower the leading edge. For this purpose the upper part of the upright 4 is provided with a series of vertically aligned holes, 18, which receive the bolts, 19, which hold the wings in place. If it is desired to adjust the trailing edge of the wing, it is done in a similar

manner, using the vertically aligned holes, 20, in the brace, 5.

In order that the outer ends of the wings may be adjusted upwardly or downwardly with respect to inner ends to vary the dihedral angle, I provide struts, 21-21a and 22-22a. Each strut is connected at one end to a lateral wing member near the outer end thereof, and at the other end is connected to the fuselage. The front struts are connected to the axle, 6, in any suitable manner, such as by means of bolts. The other ends of the struts are adjustably connected to the wings. For this purpose, the ends of the struts are provided with series of holes, 23, which receive the bolts or wires which fasten the strut to the wing.

The elevator (Fig. 3) may consist of a pair of spaced members, 25 and 26, which straddle the member 1. The members 25 and 26 carry the spaced cross pieces, 27 and 28. The forward ends of the cross pieces are provided with holes to receive a bolt, 30, which pivotally fastens the elevator to the member 1. An adjusting arm 31 is pivotally fastened to member 1 by a bolt, 32 by means of which the angle of incidence of the elevator can be varied. The arm, 31, is provided with series of holes, 33, to receive a bolt, 34, which adjustably fastens the arm, 31, to the elevator member. The outer ends of the members, 27 and 28, are connected by slack cords, 35-35a and 36-36a, to which the covering is attached.

The elevator may also be made of two independently adjustable sections as shown in Fig. 4. In this case the members, 27a and 28a, which correspond to the members 27 and 28, are not connected together, but are separately hinged to the fuselage. End braces, 49 and 24, may or may not be used.

The rudder consists of a curved piece of wire 48, each end of which is threaded and passes through a hole, 38-39, in member 1. Suitable nuts, 41, hold the wires in place.

The framework of the kite is covered with a suitable paper or cloth 55. The covering on the wings and elevator is made slack so that the wind will cause it to belly against the bowed framework. To accomplish this, the wing covering is made somewhat wider than the frame and secured to the frame at the leading and trailing edges, as shown in Figs. 5 and 6. The outer ends 17 and 17a of the wing covering and preferably but not necessarily the inner ends 56 and 56a are loose and free of the frame. Because of this construction the covering can belly in the wind to provide various degrees of wing curvature (in cross section) extending all the way along the wing, without the formation of air pockets, and permitting the banked up air to escape from the ends of the wing. The result of this construction is a kite having great flying stability and great climbing ability.

In order to give the kite an appearance of a third dimension, I provide a pair of horizontally extending wing-like members, 42-42a, fastened to the nose, 9. I also provide a similar pair of wing-like members, 43-43a, extending outwardly from the fuselage between the trailing edge of the wings and the forward edge of the elevator. These wing-like members are covered with cloth or paper.

I provide a propeller, 44, which rotates freely in the wind, mounted upon a shaft, 45, extending through the nose 9. If it is desired to simulate the sound of an airplane engine, I provide

the shaft, 45, with one or more knockers, 46, which strike against hollow, drum-like members, 47, fastened to the nose 9.

The kite is flown from a single string or cord, 48, fastened anywhere on axle 6, but preferably in the center.

The ease with which this kite flies is due, principally, to the bow or curvature of the wings, which forms a concave lower face against which the wind strikes. It will be obvious that the curvature of the wing surfaces may be attained in several ways. For example, the framework may be perfectly flat, but the covering may be made oversize or slack, (that is, wider than the frame) so that the wind will cause it to belly and assume a concave position.

If it is desired to have the kite fly in a stable manner, the wings are given a fairly steep pitch and angle. If it is desired to make the kite "stunt" the pitch and angle of the wings are kept fairly flat.

I claim:

1. An airplane kite comprising a frame forming a fuselage, a substantially horizontal frame mounted on said fuselage near one end thereof forming a pair of laterally extending wing frames, a flexible covering for each of said wing frames, said covering being of greater width than the wing frame and fastened to each wing frame at the leading and trailing edge thereof, the inner and outer ends of said covering being loose and free of said wing frame whereby the wing covering will belly in the wind to provide concave lower wing surfaces when in flight and a third frame mounted on the opposite end of said fuselage from said wings forming a laterally extending elevator.

2. An airplane kite comprising a frame forming a fuselage, a pair of substantially horizontal frames mounted on said fuselage near one end thereof forming a pair of laterally extending wing frames, a flexible covering for each of said wing frames, said covering being of greater width than the wing frames and fastened thereto at the leading and trailing edges thereof, the inner and outer ends of said coverings being loose and free of said wing frames whereby each of the wing coverings will belly in the wind to provide concave lower surfaces throughout the length thereof when in flight and a substantially horizontal frame mounted on the opposite end of said fuselage from the wings forming a laterally extending elevator.

3. An airplane kite as defined in claim 2 in which the elevator frame is provided with a pair of flexible covers secured thereto on opposite sides of the fuselage, each of said covers being secured to the leading and trailing edges of the elevator frame and being loose and free of the elevator frame at the inner and outer ends thereof whereby said elevator covers will belly in the wind to provide concave lower surfaces throughout the length thereof when in flight.

4. In an airplane kite of the type described, frames forming laterally extending substantially horizontal wings, a flexible covering secured to said wing frames at the leading and trailing edges thereof, said covering at the outer ends of said wings being loose and free of said wing frames at the inner and outer edges of said coverings whereby the wing covering at the outer ends of the wings will belly in the wind to provide concave lower wing surfaces when in flight.
